UNITED STATES PATENT OFFICE.

WILLIAM H. BEVANS, OF BRIDGEPORT, CONNECTICUT, ASSIGNOR TO AMERICAN AND BRITISH MANUFACTURING COMPANY, OF NEW YORK, N. Y., A CORPORATION OF NEW YORK.

ORDNANCE.

SPECIFICATION forming part of Letters Patent No. 742,825, dated November 3, 1903.

Application filed November 18, 1902. Serial No. 131,797. (No model.)

To all whom it may concern:

Be it known that I, WILLIAM H. BEVANS, a citizen of the United States, residing at Bridgeport, in the county of Fairfield and State of Connecticut, have invented certain new and useful Improvements in Ordnance; and I do hereby declare the following to be a full, clear, and exact description of the invention, such as will enable others skilled in the art to which it appertains to make and use the same.

This invention relates to improvements in ordnance; and the object is to provide an improved hand-operated means for readily and conveniently firing guns so constructed and arranged that large guns may be fired with the same facility as small ones.

With the above object in view the invention consists in the novel features of construction hereinafter fully described, particularly pointed out in the claims, and clearly illustrated by the accompanying drawings, in which—

Figure 1 is a side elevation of a portion of a gun with my invention applied thereto. Fig. 2 is a horizontal section through the firing attachment; Fig. 3, a transverse section on line 2 2 of Fig. 2; Fig. 4, an elevation of a modified form of the invention, and Fig. 5 a horizontal section through the same.

Referring now more particularly to said drawings, 6 designates the gun, 7 the lanyard, and 8 the mount. Revolubly mounted upon a non-recoiling part of the mount 8 is a hollow drum 9, having a peripheral groove 10 formed therein to receive the lanyard 7, which lies therein, said lanyard extending around said drum and having its end secured thereto. Within the drum is a "clock-spring" 11, having one end secured to the mount and its opposite end to the drum. Attached to a non-recoiling part of the mount in close proximity to the drum is a bracket 12, formed with a laterally-extending bearing 13 and a pistol-grip 14. Mounted in said bearing is a shaft 15, to which the upper end of a trigger 16 is attached. Also attached at its upper end to said shaft is a crank-arm 17, to the lower end of which a link 18 is pivoted. The opposite

end of the link is pivotally connected to one end of a connecting-rod 19, the opposite end of said rod being pivotally connected to the drum eccentrically of the pivotal point of the latter.

In operation a pull upon the trigger causes the drum to rotate slightly through the medium of the link and connecting-rod and exert a pull upon the lanyard, effecting the firing of the gun. As the gun recoils, the lanyard is unwound from the drum and the latter rotated against the tension of the spring. The outside circumference of the drum is approximately equal to the length of recoil of the gun, so as to provide as small a rotation of the drum as possible in taking up the lanyard when the gun returns to battery, whereby the trigger is but slightly moved. This is also provided for by connecting the trigger with the drum, as hereinbefore illustrated. When the gun returns to battery, the slack in the lanyard is taken up by the drum, which is rotated by the spring in a reverse direction.

In the modification a drum 20 is provided, which is pivotally mounted upon a non-recoiling part of the mount and is grooved peripherally to receive the lanyard which is attached thereto, as hereinbefore described. Said drum is also provided with a clock-spring 21. The pistol-grip, trigger, connecting-rod, crank, and link are not used in this modified construction; but in lieu thereof the drum is formed with a circular handhold 22, by means of which the drum may be rotated to fire the gun. When the gun recoils, the handhold turns in the hand of the operator.

From the above description it will be seen that I have provided a firing device by means of which a pull may be exerted upon the lanyard to fire the gun, said device being fixed relatively to the movement of the gun in recoil and returning to battery, whereby the lanyard will not be jerked out of the hand of the operator by the recoil of the gun, so that large guns may be fired with the same facility as small ones, and that I have also provided means to take up the slack of the lan-

yard when the gun returns to battery, the attachment being simple in construction and capable of being readily applied.

Having thus fully described my invention, 5 what I claim as new, and desire to secure by Letters Patent of the United States, is—

1. The combination in a recoiling gun and mount therefor, of a drum mounted to rotate upon a non-recoiling part of the mount, a firing-lanyard attached to and extending around the periphery of the drum, a spring connected with said drum and arranged to rotate the same to take up the slack in the lanyard after recoil of the gun, and means for effecting the 15 movement of said drum to exert a pull upon the lanyard to fire the gun.

2. The combination in a recoiling gun and mount therefor, of a drum mounted to rotate upon a non-recoiling part of the mount, a firing-lanyard attached to and extending around the periphery of the drum, a spring connected with said drum and arranged to rotate the same to take up the slack in the lanyard after recoil of the gun, a trigger arranged adjacent 20 to the drum, and an operative connection between the trigger and drum eccentric of the pivotal point of the latter.

3. The combination in a recoiling gun and mount therefor, with the firing-lanyard, of 30 means carried by a non-recoiling part of the mount for operating the lanyard to fire the gun, arranged to permit the lanyard to move rearwardly during recoil of the gun, and a spring placed under tension by the rearward 35 movement of the lanyard adapted to take up the slack in the latter caused by the recoil of the gun.

4. In a recoiling gun and mount therefor, the combination with the lanyard, of a rotatable member mounted on a non-recoiling 40 part of the mount and to which the lanyard

is connected, and a spring connected with said rotatable member and arranged to offer resistance to the rearward rotation thereof.

5. In a recoiling gun and mount therefor, 45 the combination with the lanyard, of a rotatable drum mounted on a non-recoiling part of the mount and to which the lanyard is attached, said lanyard extending around the periphery of said drum, and a spring connected with said drum and arranged to offer resistance to the rearward rotation thereof.

6. In a recoiling gun and mount therefor, the combination with the lanyard, of a rotatable member mounted on a non-recoiling 50 part of the mount, and to which the lanyard is attached, a spring connected to said member and arranged to offer resistance to the rearward rotation thereof, a trigger mounted in close proximity to said member, and an 55 operative connection between said trigger and rotatable member arranged to effect the rotation thereof in a forward direction when the trigger is operated.

7. In a recoiling gun and mount therefor, 65 the combination with the lanyard, of a drum mounted to rotate on a non-recoiling part of the mount and to which the lanyard is attached, a spring connected to said drum and arranged to offer resistance to the rearward 70 rotation thereof, a trigger mounted in close proximity to the drum, a connecting-rod pivotally connected to the drum eccentric of the pivot of the latter, and a link pivotally connecting the trigger and connecting-rod.

75 In testimony whereof I affix my signature in presence of two witnesses.

WILLIAM H. BEVANS.
